(57) **CLAIM**

The ornamental design for ergonomic nugget for chopsticks, as shown and described.

DESCRIPTION

FIG. 1 is a perspective view of the rear side of the ergonomic nugget showing my new design, as seen in use in a hand with chopsticks in the open posture, where the ergonomic nugget is attached to the top chopstick;

FIG. 2 is a perspective view of the top side of the ergonomic nugget showing my new design, as seen in use in a hand with chopsticks in the closed posture, where the ergonomic nugget is attached to the top chopstick;

FIG. 3 is a top plan view thereof;

FIG. 4 is a front view thereof;

FIG. 5 is a bottom plan view thereof;

FIG. 6 is a rear view thereof;

FIG. 7 is a left side view thereof;

FIG. 8 is a right side view thereof;

FIG. 9 is a perspective view showing the front side, the top side, and the right side thereof;

FIG. 10 is a perspective view showing the front side, the top side, and the left side thereof;

FIG. 11 is a perspective view showing the rear side, the top side, and the right side thereof;

FIG. 12 is a perspective view showing the rear side, the bottom side, and the right side thereof;

FIG. 13 is a perspective view showing the rear side, the top side, and the left side thereof;

FIG. 14 is a perspective view showing the rear side, the bottom side, and the left side thereof;

FIG. 15 is a zoomed-out view of FIG. 1, showing the rear side of the ergonomic nugget attached to a top chopstick, where chopsticks and a hand are shown in full without clipping; and,

FIG. 16 is a zoomed-out view of FIG. 2, showing the top side of the ergonomic nugget attached to a top chopstick, where chopsticks and a hand are shown in full without clipping.

In FIG. 1, FIG. 2, FIG. 15, and FIG. 16, chopsticks and the hand are shown in broken lines for illustrative purposes only, and form no part of the claimed design.
